Victor J. Evans
ATTORNEY

UNITED STATES PATENT OFFICE.

HENRY C. HETTINGER, OF CHICAGO, ILLINOIS.

UPHOLSTERING BRACE.

Application filed February 6, 1922. Serial No. 534,518.

To all whom it may concern:

Be it known that I, HENRY C. HETTINGER, a citizen of the United States, residing at Chicago, in the county of Cook and State 5 of Illinois, have invented new and useful Improvements in Upholstering Braces, of which the following is a specification.

This invention relates to a brace particularly designed for bracing and supporting 10 the upholstering on dining room or analogous chairs which are so constructed that the upholstering itself can comprise only the webbing as a brace.

It is a well known fact that particularly 15 in dining room chairs, the upholstering breaks down or sags after use and continued use after said sagging causes cracking or tearing of the cover of the upholstered portion requiring repairs or re-upholstering of 20 the chair, and further that such breaking down or sagging of the upholstering is unsightly as well as uncomfortable even before it reaches the stage where repairs are necessary.

25 It is an object of this invention to provide a brace structure for bracing such upholstering and maintaining it in its proper position against sagging or breaking down under the weight of persons sitting upon the 30 chair, which brace may be manufactured and applied at a much less cost than the cost of re-upholstering the chair, and further to provide a brace which is resilient and will not detract from the cushioning 35 effect of the chair, and also a brace which can be used on new and old chairs alike, keeping the upholstered seat in its bulged up position and causing it to maintain its new appearance indefinitely.

40 A further object of the invention is to provide a spring brace or construction which may be easily attached to old chair seats, without disturbing the upholstering, by anyone without requiring any knowledge 45 of upholstering as well as one which is constructed and designed to prevent breaking, or any part of it from getting out of order.

Other objects of the invention will appear 50 in the following detailed description taken in connection with the accompanying drawing wherein:

Fig. 1 is a perspective of the improved upholstering brace showing it applied to a flat bottom upholstered chair.

55 Fig. 2 is a perspective of one of the sections of the upholstering brace.

Fig. 3 is a fragmentary section through the chair bottom showing the manner of applying the brace to new chairs.

Fig. 4 is a section through the chair bottom showing a slight modification of the brace.

Fig. 5 is a bottom plan of the modified form of the brace.

Referring more particularly to the drawings, the preferred form of the improved brace for the upholstering of flat bottom chairs, comprises a pair of members 1 and 2 which are similar in construction, being interchangeable to provide a right hand and 70 a left hand member as clearly shown in Fig. 1 of the drawings. These members 1 and 2 are each constructed of a single length of spring wire and they have their ends bent substantially at right angles to their 75 major portions as shown at 3 providing prongs for insertion through the barrel portion 4 of clips 5 which are attached to the inner edges of the wooden bottom A of a chair B as shown in Fig. 1 of the drawings 80 when the improved braces are applied to an old chair. When the braces are applied to a new chair in the application of the upholstering C thereto, the angled ends 3 are inserted in sockets or recesses 6 formed in 85 the wooden base A adjacent the inner edges of the wooden base or seat. The wires 81 of which the members 1 and 2 are constructed are coiled adjacent to the angled ends 3 to provide a plurality of spring convolutions 7 90 for providing resiliency and cushioning action to the brace to permit its application to a chair without destroying the cushioning application of the upholstering C 95 thereon.

Transversely extending substantially U-shaped portions 8 are formed upon each of the members 1 and 2 intermediate the end convolution 7 and the bight portions 9 of these substantially U-shaped portions are 100 adapted to be attached to the chair bottom A by clips or fasteners 10 so as to provide a three point connection for each of the members 1 and 2 with the chair bottom. While in the drawings relatively sharp corners 11 are shown it is to be understood that these corners may be rounded upon any desired radius without departing from the spirit of this invention, and the provision of the transversely extending portions 8 provide substantially four independently acting upholstering springs which maintain the 105 110

original bulge to the upholstering, preventing it from sagging or breaking down into the opening in the seat A, the transversely extending portions 8 acting as upholstering springs, while the parallel adjacent portions of the members 1 and 2 act as other springs which provides the substantially four separate upholstering springs in the chair structure.

- 10 It will be readily apparent that by spreading the legs of the transversely extending extensions 8 or by forcing them closer together that the members 1 and 2 may be sized to fit any size dining chair seat and it 15 will also be apparent that the improved upholstering springs may be attached to chairs after the upholstering has sagged, for the purpose of re-bulging the upholstering and supporting it in its proper position, eliminating liability of cracking or tearing of the 20 cover of the upholstering; and that they are also equally adaptable for attachment to new chairs during their construction. A clip 5 is provided for each angled attaching end and if necessary the adjacent clips may be spaced to permit proper adjustment of the members 1 and 2 to a chair bottom. The upholstering springs are constructed so 25 as to prevent any tipping strain, the springs serving to keep themselves free to act at all 30 times and in all positions of the chair, and also that they may be attached by any person unskilled in the art of upholstery.

In Figs. 4 and 5 of the drawings a slight modification of the upholstering spring is illustrated, this modified form comprising a plurality of single lengths 20 of spring wire which are coiled intermediate their ends to provide resilient or spring convolutions 35 and the ends of the wires 20 are angled 40 as shown at 22 and seated in the attaching strips 23 which attaching strips may be at-

tached by nails, screws, or the like to the inner edges of the bottom A of a chair as shown in Fig. 4 of the drawings. It is, of course, to be understood that a plurality of wires 20 are to be used the number depending upon the size of the chair bottom to be braced.

While in the foregoing description and in the drawings the improved upholstering brace has been designed and shown applied to an upholstered dining room chair, it is to be understood that they may be applied to any flat bottom upholstered chair seat 55 or analogous structure without departing from the spirit of this invention.

It is, of course, to be understood that the invention may be constructed in other manners and the parts associated in other relations and, therefore, I do not desire to be limited in any manner except as set forth in the claim hereunto appended.

Having thus described my invention what I claim is:

In a chair, the combination of an open seat frame, opposite portions of which are provided with vertically disposed sockets, upholstering connected with and arranged immediately above said frame, and members having major portions arranged immediately under and against the said upholstering and also having pendent end portions disposed in said sockets; each of the said members being provided with an outwardly extending loop arranged immediately under and against the upholstering and hingedly connected with a portion of the frame, and each member being also provided with pendent convolute springs arranged at points between the said loop of the member and the pendent ends thereof.

In testimony whereof I affix my signature.

HENRY C. HETTINGER.
